FOLDING UMBRELLA

Carl R. Geisel, Windsor, Conn., assignor of one-half to Eugene A. La Brie, Hartford, Conn.

Application May 16, 1933, Serial No. 671,336

15 Claims. (Cl. 135—25)

My invention relates to folding umbrellas and more particularly to that class of umbrellas which can be collapsed into a small and compact form which will fit into a small compartment such as in a lady's handbag, a traveling bag or a pocket.

The object of my invention is primarily to provide an umbrella of the character described which is simple in its operation.

10 A further object is to provide such an umbrella which is durable and so constructed that it is strongly braced when in its open position.

15 An improved umbrella comprising my invention and by which the objects above set out may be attained, is illustrated in the accompanying drawing in which:

20 Figure 1 is a view of the umbrella as it appears in its open position, but showing only two of the oppositely disposed ribs for the purpose of simplifying the illustration.

Figure 2 is a view showing the same in a partly closed position.

25 Figure 3 is an enlarged view showing the umbrella completely collapsed; the bottom portion 25 of the staff and handle being shown in central vertical section.

30 Figure 4 is a view similar to Figure 3, but showing the position of the umbrella at the start of the opening operation; the lower portion of the umbrella only being shown.

Figure 5 is a further enlarged view in central vertical section on a line between the ribs, with some of the parts broken away; the staff being shown in collapsed position while the umbrella 35 is in its open position.

Figure 6 is a detail view showing the construction of the staff sections.

Referring to the drawing in which like reference numerals denote corresponding parts in the 40 different views, the numeral 5 indicates a staff and 6 a handle secured to the end thereof. The said staff is composed of telescoping sections 7, 8 and 9. Each of the sections 7 and 8 is reduced at the bottom thereof to form tapered walls 10. The upper ends of the sections 8 and 9 are provided with expanding tapered walls 11 which, when the staff is extended, will engage the tapered walls 10 and thus form a frictional lock to retain said sections securely in the extended 50 position.

In order to provide a more secure engagement between the sections, I provide bushings 12 which are rigidly secured to the upper ends of the sections 8 and 9, and which form the tapered walls 55 11 above described.

These bushings may be made of a metal such as brass or of some material which is softer than the material in the staff sections and thus provide a better locking action between the tapered surfaces of the corresponding sections.

5 A collar 13 is rigidly secured to the top of the staff section 7. The lower portion of the said collar is provided with a projection 14 in which is formed an annular locking groove 15 and the upper portion of said collar is provided with a 10 threaded extension 16.

A tubular runner 17 is slidably mounted on the top section of the staff 5, and has a camming flange 18 and a tubular extension 19 extending above the said flange.

15 A collar 20 is slidably mounted on the said extension 19 and the said extension is flared outwardly at the top thereof, as at 21, to limit the sliding movement of said collar thereon.

The handle 6 is threaded to the section 9 of the 20 staff as at 22, and is provided with a recess 23 to receive the runner 17 when the umbrella is collapsed as clearly shown in Figure 3.

A cap 24 is threaded to the extension 16 of the collar 13, and is provided with recesses 25 in the 25 top thereof to receive a wrench for turning the same.

A spring locking pin 26 is secured to the said cap 24. The said pin is provided with a head 27 and has slots 28 for permitting expansion and 30 contraction of the said head. A locking groove 29 is formed at the inside of the section 9 to be engaged by the said locking pin head 27 when the staff of the umbrella is collapsed as illustrated in Figure 5.

35 Collapsible ribs 30 are provided. These ribs are constructed in a form commonly known as lazy tongs, and comprise a series of one or more tong sections which are pivoted together at their ends.

40 As illustrated in the drawing, I have shown each of these ribs having two tong sections. The first of said sections comprising a link 31 which is pivoted to the collar 20 and has an offset portion 32 formed to support the cover 33 of the 45 umbrella when the said umbrella is in its open position, and a link 34 that is pivoted to the collar 13, extends across the link 31 and is pivoted thereto as at 35. The second of said sections is formed by the link 36 which is pivoted to the end 50 of the link 32 and the offset link 37 which is pivoted to the end of the link 34; both of the links 36 and 37 being pivoted together at 38. A top supporting link 39 is pivoted to the end of the link 37. A bracing link 40 is pivoted to the end 55

of the link 36, and to the link 39 as at 41. Tips 42, such as commonly used on umbrellas are provided at the ends of the links 39 to which is attached the umbrella cover 33 by means of sewing the said cover thru openings in the said tips. 5

The pivots 43, connecting the link sections adjacent the umbrella cover, are tubular in construction to provide openings 44 thru which is sewed the cover 33.

10 The links 40 are provided with cam engaging extensions 45.

When the ribs are extended to the open position as shown in Figure 1, the extensions 45 engage the links 37 of the adjacent tong sections, 15 thus preventing further closing of said tong sections and retaining the relation of the rib sections in a position which will render a strongly braced rib.

In order to secure the umbrella cover 33 at the 20 center thereof, I provide a ring 46 to which the said cover is sewed. The said ring fits over and surrounds the extension 16 of the collar 13. A washer 47, preferably of leather, is provided over the said ring and pressed firmly in engagement thereon by the cap 24 which is threaded to said extension. 25

To retain my improved umbrella in its open position, I provide a hook 48 which is pivoted on the collar 20 and located between two of the 30 ribs 30. The said hook is provided with a cam tail 49 which projects thru an opening 50 in the camming flange 18. A spring 51 is provided to force the said hook into engagement with the locking groove 15 when the umbrella is in its 35 open position.

In order to minimize the friction between the various links at their pivotal connections, I provide spacing washers 52 at each point where the links are pivoted together.

40 The operation of my improved umbrella is as follows:

When it is desired to open the said umbrella from its collapsed position illustrated in Figure 45 3, the handle 6 is pulled downwardly extending the staff to the position shown in Figure 1. The runner 17 is then pushed upwardly causing the cam 18 to engage the cam engaging extensions 45 on the ribs and force them outwardly thus starting the opening operation of the umbrella as 50 clearly illustrated in Figure 4.

Raising the said runner will also disengage the tail 49 of the hook 48 permitting the said hook to be moved forward by the action of the spring 51. A continuation of the operation of raising 55 said runner 17 will open the umbrella thru the position shown in Figure 2 to the completely open position shown in Figure 1. When the umbrella is about to reach its completely open position, the hook 48 will engage the locking groove 15, in the collar 13, and thus retain the umbrella in 60 the said open position. Thus, the extending of the staff 5 and the raising of the runner 17 thereon, may be performed in one single manual operation which will result in opening the umbrella 65 from its entirely collapsed position shown in Figure 3, to its entirely opened position shown in Figure 1.

In closing the said umbrella from the position 70 shown in Figure 1, the same is held by the handle 6 in one hand and the runner 17 is grasped in the other. The said runner is pulled downwardly, lowering the cam 18 and forcing the tail 49 of the hook 48 inwardly, releasing the hook from its engagement with the locking 75 groove 15. Continuing the lowering of the said

runner will close the umbrella back thru the position shown in Figure 2 to that shown in Figure 3. The operation of collapsing the staff being completed by forcing upwardly on the handle 6 after the ribs have been collapsed. 5

While I have shown and described an umbrella by which the above objects are attained, it is to be understood that the construction of the same may be changed to a greater or lesser extent without departing from the scope of my invention as set out in the following claims. 10

I claim:

1. In a folding umbrella having a staff, a stationary collar, and a sliding collar on said staff, a plurality of collapsible ribs each comprising 15 links pivoted together to form a rib of lazy tong construction, each of said ribs having one side thereof pivotally connected to said stationary collar and the other side thereof pivotally connected to said sliding collar, and offset portions in said 20 links conforming with the shape of, and adapted to support, said cover.

2. In a folding umbrella having a staff, and a stationary collar on said staff, a runner slidably mounted on said staff, a sliding collar on said 25 runner, and a plurality of ribs of lazy tong construction being pivotally connected to said stationary collar and to said sliding collar.

3. In a folding umbrella having a staff, a stationary collar on said staff, a runner slidably mounted on said staff, a collar slidably mounted on said runner, and a plurality of ribs of lazy 30 tong construction each being pivotally mounted to said stationary collar by one side thereof and by the other side thereof pivotally mounted to 35 the collar on said runner.

4. In a folding umbrella having a slidably mounted collar and a plurality of ribs of lazy tong construction; means on said ribs for limiting the opening movement thereof. 40

5. In a folding umbrella having a top, a telescoping staff and a collar secured to said staff and stationary thereon; a runner slidably mounted on said staff having a cam thereon and a collar slidably mounted on said runner, a plurality of 45 lazy tongs comprising opening and closing ribs pivoted at one side thereof to said stationary collar, and at the other side thereof to the collar on said runner, cam engaging projections on said lazy tongs adapted to rest in operative relation 50 with said cam, when the said lazy tongs are closed, to be moved by said cam for starting the opening operation of said ribs.

6. In a folding umbrella having a staff and a stationary collar having locking means therein 55 mounted on said staff, a runner slidably mounted on said staff, a collar slidably mounted on said runner, a plurality of opening and closing ribs having one side thereof pivoted to said stationary collar and the other side thereof pivoted to said collar for opening and closing operation thereby, and releasable means mounted on said collar and adapted to engage said locking means to retain said umbrella in its open position.

7. In a folding umbrella having a staff, a plurality of ribs pivoted thereon, and locking means in said staff, a runner slidably mounted on said staff, a collar slidably mounted on said runner and connected to said ribs for opening and closing the same, and a hook on said collar adapted to engage said locking means to retain the said umbrella in its open position. 65

8. In a folding umbrella having a staff with a locking detent therein, a plurality of ribs pivoted on said staff and a runner slidably mounted on 70 75

5 said staff, a collar slidably mounted on said runner and pivotally connected with said ribs to open and close the same, a hook pivoted on said collar, a spring adapted to cause said hook to engage the said locking detent to retain the umbrella in its open position, and a cam on said hook adapted to be operated by the said runner to release said hook from the locking detent.

10 9. In a folding umbrella having a staff comprising a plurality of telescoping tubular sections and a cap mounted to the top end section of said staff; a spring locking means in said cap adapted to engage the bottom end section when the said staff is closed to retain the said sections in the closed position.

15 10. In a folding umbrella having a collapsible staff comprising a plurality of tubular sections telescoped one within the other, an inwardly tapered portion in the wall at one end of each of said sections, and a friction locking sleeve, secured to the section telescoping within the same, to engage said inwardly tapered wall for retaining the said staff in its open position.

20 11. In a folding umbrella having a staff and a stationary collar mounted on said staff, a grip portion on said runner, a collar slidably mounted on said runner above said grip portion, a runner slidably mounted on said staff, a plurality of collapsible ribs pivoted to said stationary collar and to said slidably mounted collar and a handle secured to said staff, the said handle and grip portion only of said runner adapted to telescope one within the other.

25 12. In a folding umbrella having a collapsible staff having means for retaining the same in open position and means for retaining it in closed position, a stationary collar secured to said staff and having a downwardly extending portion with a locking groove therein, and a runner slidably mounted on said staff, a collar slidably mounted on said runner, a hook pivoted on said slidable

30 collar and adapted to engage said locking groove to retain said umbrella in its open position, a flange on said runner forming a starting cam for the opening operation of said umbrella, an opening in said flange, a cam extension on said hook projecting thru said opening in said flange to actuate said hook for releasing it from said locking groove, said stationary collar having a recess in the downwardly extending portion thereof into which is received a portion of said runner, and a plurality of opening and closing ribs of lazy tong construction pivoted to the stationary collar on said staff and to the sliding collar on said runner, and adapted to be partially opened by the said starting cam.

35 13. In a device of the character described having a staff, a stationary collar on said staff and a runner slidably mounted on said staff, a slidable collar on said runner, and a plurality of ribs pivotally connected to said collar.

40 14. In a device of the character described having a staff, a collar secured to said staff, and a runner slidably mounted on said staff, a cam on said runner, a collar slidably mounted on said runner, a plurality of opening and closing ribs pivoted at one side thereof to said stationary collar and at the other side thereof to the collar on said runner, and cam engaging projections on said ribs adapted to be engaged by said cam for starting the opening movement of said ribs.

45 15. In a device of the character described, a collapsible staff comprising a plurality of tubular telescoping sections, an inwardly tapered portion in the wall of each of said sections and a tapered friction locking sleeve, of a material different than that of said sections, secured to the section telescoping within another of said sections to engage said inwardly tapered wall for retaining the said staff in its open position.

50 CARL R. GEISEL.
